(57) **CLAIM**

The ornamental design of an electronic device, substantially as shown and described.

DESCRIPTION

FIG. 1 is a top perspective view of the electronic device according a first embodiment.

FIG. 2 is a top view of the electronic device according to the first embodiment.

FIG. 3 is a left side view of the electronic device according to the first embodiment.

FIG. 4 is a front view of the electronic device according to the first embodiment.

FIG. 5 is a right side view of the electronic device according to the first embodiment.

FIG. 6 is a rear view of the electronic device according the first embodiment.

FIG. 7 is a bottom view of the electronic device according to the first embodiment.

FIG. 8 is a bottom perspective view of the electronic device according to the first embodiment.

FIG. 9 is a top perspective view of the electronic device according a second embodiment.

FIG. 10 is a top view of the electronic device according to the second embodiment.

FIG. 11 is a left side view of the electronic device according to the second embodiment.

FIG. 12 is a front view of the electronic device according to the second embodiment.

FIG. 13 is a right side view of the electronic device according to the second embodiment.

FIG. 14 is a rear view of the electronic device according the second embodiment.

FIG. 15 is a bottom view of the electronic device according to the second embodiment; and,

FIG. 16 is a bottom perspective view of the electronic device according to the second embodiment.

The broken lines showing the remainder of the electronic device are directed to environment. The broken lines on the top surface within the claimed design in the second embodiment are for illustrative purposes only. None of the broken lines form a part of the claimed design. The upper portion of the electronic device is transparent or translucent.
